STACY B. HASELTINE, OF CHICAGO, ILLINOIS, ASSIGNOR TO W. H. MINER, INC., OF CHICAGO, ILLINOIS, A CORPORATION OF DELAWARE.

DOOR-OPERATING MECHANISM FOR REFRIGERATOR CARS.

Application filed January 16, 1926. Serial No. 81,619.

This invention relates to improvements in door operating mechanism for refrigerator cars.

An object of the invention is to provide a door operating mechanism for refrigerator cars of simple design, wherein the shaft of the operating mechanism is given a rolling movement parallel to the face of the door, and wherein the ends of the shaft have actuating portions offset with respect to the axis of the shaft, which actuating portions cooperate with keepers on the car to effect movement of the door in opening and closing directions.

Other objects and advantages of the invention will more clearly appear from the description and claims hereinafter following.

In the drawings forming a part of this specification, Fig. 1 is a side elevation of a portion of a refrigerator car showing the doors thereof and my improvements in connection therewith. Fig. 2 is a broken vertical sectional view of the invention substantially on line 2—2 of Fig. 1, showing parts of the mechanism in side elevation and parts in cross-section. Fig. 3 is a horizontal, sectional view on an enlarged scale, taken on the line 3—3 of Fig. 1. And Fig. 4 is a horizontal, sectional view on an enlarged scale taken on the line 4—4 of Fig. 2, showing the lower door keeper in elevation with the operating shaft partially in section, and indicating in dotted lines the position of the operating shaft and door when the same is at the limit of the opening operation.

In the drawings, 10 and 11 designate hinged refrigerator car doors, said doors being provided with beveled meeting edges, as indicated at 12, in the usual manner, and suitable packings are provided on said meeting edges and also around the outer edges of the doors and door frame. The doors 10 and 11 are swingably supported on the usual hinge members 13—13. As is customary, the operating shaft is mounted on the last door to be closed—that is, the door 11 in the structure as shown. When the door 10 has been finally closed it may be secured by the usual latch 12'.

The improved door operating mechanism comprises broadly, a shaft A; a pivoted operating handle B; a pair of guide brackets C—C; a pair of actuating elements D—D; and a pair of keepers E—E.

The operating shaft A, as shown, comprises an intermediate connecting member 14,

which, in the present invention, is made up of a section of pipe of suitable diameter, the pipe section being compressed adjacent the lower end to provide a flat portion 15, upon which is pivotally mounted the forked end 16 of the usual handle B, the rivet 17 being utilized to pivotally secure the forked portions of the handle end to the flat portion 15. The opposite ends of the shaft A are provided with end members 18—18, which are similar in construction, and a detailed description of the construction of one will suffice for both, similar reference characters being utilized to designate like parts. Each end member 18 preferably is of composite construction and includes a hollow mutilated gear 19, provided with a sleeve 20, and preferably cast within the gear 19 and sleeve 20, is the intermediate portion 21 of the operating element, the portion 21 being provided with an abutment 22 against which the inner end of the sleeve 20 bears. Inwardly of said abutting portion is a collar 23, and inwardly of said collar is a shank 24, said shank fitting within the end of the pipe section and being secured therein by rivets 25, the collar 23 bearing against the edges of the pipe section, and in the case of the lower end of the shaft, resting against the guide bracket G to support the shaft. The outer end of the operating member is provided with the actuating element D, including the crank arm 26, and projecting pin 27 which is adapted to cooperate with the related keeper E in a manner hereinafter more fully described.

The opposite ends of the shaft A extend through the guide brackets C—C, which are mounted adjacent the upper and lower edges of the door 11. Each of said brackets comprises an inner wall 28 secured to the door face by a plurality of bolts 29, the heads of said bolts being disposed in recesses 30 in the outer face of said inner wall. Side walls 31 are provided, and spaced from the inner wall 28, and offset with respect to said inner wall and connecting said side walls, is an outer wall 32. The inner face of the outer wall 32 is provided with a rack 33 adapted to cooperate with the teeth of the mutilated gear 19, as best shown in Figure 3.

The keepers E—E are secured to the door frame in line with the operating shaft, each keeper having webs 34 through which the securing bolts are extended. Each keeper E is provided with a recess 35, the walls 36 of

said recess for the major portion thereof being disposed in substantially parallel relation with the face of the door frame, and with each other, said walls being thereafter curved outwardly, as indicated at 37, and at their extremities providing an opening 38 for the entrance of the pin 27 of the actuating member D to the recess in the keeper.

The operation of my improved door operating mechanism is as follows, assuming the parts to be in the position shown in Fig. 1. In opening the door the shaft A is rotated by moving the handle B counter-clockwise away from the door 10. Due to meshing of the gears 19 with the racks 33, the shaft A will roll along the surface of the door in a direction toward the left and through a plane parallel with the face thereof. During this movement of the shaft, the crank arms 26 and pins 27 will be rotated about the axis of the body portion of the shaft A, the pins 27 bearing upon the inner straight walls 36 of the keepers E—E to force the door outwardly, such movement continuing until the shaft has moved to a point beyond the straight portions 36, when the pins 27 will bear upon the inner curved walls 37 of the keepers, the translation of the shaft due to meshing of the gears 19 with the racks 33, and the rotation of the cranks, being continued until the parts are in the position indicated in dotted lines in Fig. 4, whereupon the door may be swung freely to open position. Upon swinging the handle in the reverse direction, the shaft A will be rotated in the opposite direction to that heretofore described, and effect a rolling movement of the shaft and rotation of the cranks in a reverse direction to that which they had during the door opening operation. At the inception of the door closing operation, it will be noted that due to placing the racks 33 upon the inner faces of the outer walls of the brackets, that the direction of rotation of the pins 27 is substantially in the direction of travel of the shaft toward the right, as viewed in Fig. 1, so that the pins 27 are quickly moved into engagement with the openings 38 of the keeper. Continued movement of the pins 27 will cause the same to bear upon the outer walls 36, causing the door to be forced inwardly. This action will continue until the shaft and cranks have assumed the position shown in full lines in Fig. 4, when the door will be tightly closed.

It will be observed that the above described arrangement permits the use of keepers which have walls disposed parallel with the face of the door, and hence affords a locking surface which prevents undesirable movement ordinarily occurring in constructions where the engaging faces of the keepers are inclined outwardly with respect to the door frame. It also should be noted that when the shaft and cranks are in fully closed

position, the shaft and crank pins 27 are aligned substantially at right angles to the face of the door, which affords a much better lock than that provided in constructions where the crank and shaft are offset when in locked position, this arrangement being permitted by the combined movable shaft and the crank means thereon. Another important feature of the invention resides in placing the racks, which cooperate with the gears on the shaft to effect translation thereof, upon the inner surfaces of the outer walls of the guide brackets, as this effects a more rapid and efficient engagement, and disengagement, of the pins 27 with the keepers, as it will be appreciated that the pins 27 tend to roll over the keeper walls during a closing operation, rather than sliding thereon.

While I have herein shown and described what I now consider the preferred manner of carrying out the invention, the same is merely illustrative, and I contemplate all changes and modifications that come within the scope of the claims appended hereto.

I claim:

1. In a device of the character described, the combination with a member having a door opening and a hinged door; of means for opening and closing said door, including a rotary shaft having crank means which is provided with an actuating portion offset with respect to said shaft; keepers on said member adapted to be engaged by said offset portions to effect opening and closing movement of said door; guide brackets mounted on the door adjacent the ends of said shaft and cooperating therewith; and rack and gear connections between said shaft and said brackets for causing rolling movement of said shaft, said gear being disposed between the rack and the door.

2. In a device of the character described, the combination with a member having a door opening and a hinged door; of means for opening and closing said door; including a rotary shaft having crank means, each of which is provided with an actuating portion offset with respect to said shaft; keepers on said member adapted to be engaged by said offset portions to effect opening and closing movement of said door; guide brackets mounted on the door adjacent the ends of said shaft, each of said brackets including an inner wall secured to the door and an outer wall provided with a rack; and a gear on said shaft located adjacent each bracket and adapted to engage with the rack thereon.

3. As an article of manufacture, a hollow door operating shaft in the form of a pipe section, said shaft having operating end portions thereon, each of which comprises a hollow gear member and an operating element fixed within said gear member and having a shank at one end, said shank being disposed in the hollow end of said shaft and fixed

thereto, and the other end of said operating member comprising an actuating portion, said gears being adapted to coact with brackets on a car door, and said actuating portions 5 being adapted to coact with keepers on the door frame.

4. In a door operating mechanism, the combination with a member having a door opening and a pivoted door; of keeper means 10 mounted on said member, said keeper means having an entrance adjacent the free edge of said door, and having engaging surfaces extending inwardly from the free edge of said door when closed; a shaft mounted on said 15 door and provided with eccentric means adapted to engage said keeper means to effect opening and closing movement of the door, said shaft being provided with a handle adapted to be swung radially to rotate 20 said shaft; and means for effecting bodily movement of said shaft upon rotation thereof, said means operating to cause travel of said shaft toward the free edge of the door when said shaft is rotated in a counter-clockwise 25 direction, and to cause travel of said shaft in the reverse direction upon movement in a clockwise direction.

5. In a door operating mechanism, the combination with a member having a door 30 opening and a pivoted door; of keeper means mounted on said member, said keeper means having an entrance adjacent the free edge of said door, and having engaging surfaces extending inwardly from the free edge of said 35 door when closed; a shaft mounted on said door and provided with eccentric means adapted to engage said keeper means to effect opening and closing movement of the door, said shaft being provided with a handle 40 adapted to be swung radially to rotate said shaft; and means for effecting bodily movement of said shaft upon rotation thereof, said means operating to cause travel of said shaft toward the free edge of the door when said 45 shaft is rotated in a counter-clockwise direction, and to cause travel of said shaft in the

reverse direction upon movement in a clockwise direction, said means comprising guide brackets having racks spaced from the face of the door and disposed outwardly of 50 the shaft, said shaft having gears adapted to cooperate with said racks to effect the bodily movement of said shaft.

6. In a device of the character described, the combination with a member having a 55 door opening and a hinged door; of operating means for opening and closing said door, including a rotary shaft mounted on said door and having a crank member fixed thereto, and provided with an off-set actuating 60 portion thereon; keeper means having an engaging face disposed substantially parallel with the face of said member and adapted to be engaged by said actuating portion; and means co-operating with said shaft to effect 65 simultaneous bodily shifting and rotation of said shaft and actuating portion with respect to said keeper during closing of said door so as to align the axes of said actuating portion and said shaft in a plane substantially 70 perpendicular to the engaging face of said keeper means, when the door is closed.

7. In a door operating mechanism of the character described, the combination with a member having a door opening and a hinged 75 door; of means for opening and closing said door, including a rotary shaft having an angular arm portion and an actuating portion on said arm off-set with respect to said shaft, said actuating portion being free to have 80 swinging movement; co-acting means on said shaft and door for simultaneously effecting bodily travel of said shaft along the face of said door and rotation of said shaft; and keeper means secured to said member and 85 adapted to be engaged by the actuating portion on said angular arm.

In witness that I claim the foregoing I have hereunto subscribed my name this 7th day of January, 1926.

STACY B. HASELTINE.
